UNITED STATES PATENT OFFICE.

CLARA M. RICE, OF ABERDEEN, SOUTH DAKOTA.

BOTTLE-CAP.

1,350,238.

Specification of Letters Patent. Patented Aug. 17, 1920.

Application filed April 26, 1920. Serial No. 376,718.

To all whom it may concern:

Be it known that I, CLARA M. RICE, a citizen of the United States, residing at Aberdeen, in the county of Brown and 5 State of South Dakota, have invented a new and useful Bottle-Cap, of which the following is a specification.

The present invention relates to milk bottle covers or closures, and it is the object of 10 the invention to provide a novel form of cover which may be readily positioned on a milk bottle to exclude dirt, dust or the like, when the usual pasteboard bottle cap has been removed.

15 A further object of the invention is to provide a cover of this character including a pair of spring arms adapted to be sprung into position around the usual milk bottle top, in a manner to permit the device to be 20 readily removed, but prevented from accidental displacement.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 30 within the scope of what is claimed, without departing from the spirit of the invention.

Referring to the drawing:—

Figure 1 illustrates the neck of a milk bottle, showing the removable cover constructed in accordance with the present invention, as applied to the mouth of the bottle.

Fig. 2 illustrates a sectional view taken on line 2—2 of Fig. 1.

Fig. 3 illustrates a rear elevational view of the cover as applied.

Referring to the drawing in detail, the device forming the subject matter of the present invention is shown as applied to 45 the mouth of a milk bottle, indicated at 5, the mouth of the bottle being provided with the usual bead.

The cover proper includes a disk-like top

6 formed preferably of sheet metal, the same having a depending annular flange 7 50 formed preferably of spring steel, the flange being curved transversely to conform to the curvature of the usual bead of a milk bottle.

This flange 7 is secured to the disk-like top 6, throughout a portion of its length, the 55 free ends of the flange overlapping each other as indicated at 8, and provide spring arms for gripping the bottle adjacent the upper end thereof to secure the cover to the bottle.

60 Forming a part of the flange 7 is an outwardly and downwardly extending portion indicated at 9, which portion 9 provides a camming means to cam the resilient arms outwardly to permit the cover to be readily 65 and easily forced into position to cover the bottle, to which the device is applied.

In the operation of the device, it is only necessary to place the cover over the mouth 70 of a bottle, force the same downwardly whereupon the spring arms expand and grip the bead of the usual bottle to maintain the cover in proper relation with the bottle, to prevent accidental displacement thereof.

If it becomes necessary to remove the 75 cover, a slight pull exerted thereon tends to expand the arms to cause the same to release their hold on the bead.

Having thus described the invention, what is claimed is:— 80

In a cover for bottles, a circular top, a curved depending flange having connection with the top throughout a portion of its length to provide spring arms, said spring arms adapted to overlap each other at the 85 free ends thereof, and means forming a part of the spring arms to cam the same outwardly to cause the arms to grip the bottle to which the same is applied.

In testimony that I claim the foregoing as 90 my own, I have hereto affixed my signature in the presence of two witnesses.

CLARA M. RICE.

Witnesses:

Dr. D. F. RICE,

Mrs. A. J. WOLBRINK.
